Primary Examiner — Cynthia Ramirez(74) *Attorney, Agent, or Firm* — Mark David Torche;
Patwrite LLC(57) **CLAIM**

The ornamental design for a nestable pallet, as shown and described.

DESCRIPTION

FIG. 1 is an isometric view of a nestable pallet, showing my new design;

FIG. 2 is a top view of the nestable pallet;

FIG. 3 is a side view of the nestable pallet;

FIG. 4 is a front view of the nestable pallet;

FIG. 5 is a bottom view of the nestable pallet;

FIG. 6 is an isometric view of a stack of two nestable pallets, in which first nestable pallet is nested on second nestable pallet; and,

FIG. 7 is a side view of the stack of two nestable pallets, in which first nestable pallet is nested on second nestable pallet.

The broken lines shown in FIGS. 6 and 7 are included for the purpose of illustrating environment and forms no part of the claimed design.
